CLAIM

The ornamental design for an exercise device as shown and described.

DESCRIPTION

FIG. 1 is a top view of an exercise device, showing our new design.

FIG. 2 is a bottom view of the claimed design.

FIG. 3 is a front view of the claimed design.

FIG. 4 is a rear view of the claimed design.

FIG. 5 is a right side view of the claimed design.

FIG. 6 is a left side view of the claimed design; and,

FIG. 7 is a perspective view of the claimed design.

1 Claim, 4 Drawing Sheets
